WARP-STOP MECHANISM FOR LOOMS.

Application filed May 26, 1926. Serial No. 111,851.

This invention relates to mechanical warp stop mechanisms for looms whereby the loom is stopped on the occurrence of a fault in the warp threads.

5 Looms are now ordinarily equipped with a warp stop motion which is intended to arrest the operation of the loom when a warp thread breaks or becomes too slack. It happens at times during the weaving operation 10 that a warp thread will become crossed over other or adjacent warp threads and produce defective cloth. The crossing of the warp thread as above noted may occur when one of the warp threads breaks between the shedding mechanism and the fell of the cloth. When this occurs, the end of the broken warp thread is liable to extend laterally over adjacent warp threads, and when the 15 shed is changed the crossed end of the broken warp thread will cause undue tension to be exerted upon some of the crossed warp threads and unless such condition is corrected, defective cloth will be woven.

20 The warp stop mechanism of the present invention provides means whereby should a cross in the warp take place and undue tension be given to one or more of the warp threads, the associated drop wire will be 25 raised by the unduly tensioned thread and cause loom stoppage.

In accordance with the present invention, the drop wires are supported in a normal position by the warp threads during weaving and provision is made to effect loom stoppage should one of the warp threads break or become too slack for weaving purposes, and also to stop the loom should one of the warp threads become unduly tensioned, thereby lifting the associated drop wire 30 above its normal position.

The invention and new combination of parts will best be made clear from the following drawings and description of one good form thereof.

35 In the drawings:

Fig. 1 is a perspective view with parts broken away showing a loom provided with the present invention;

Fig. 2 is an enlarged perspective detail 40 showing one of the warp threads as having been unduly tensioned and thereby lifting its associated drop wire to effect loom stoppage;

Fig. 3 is a side elevation showing the drop

wire detector constituting a feature of the 55 present invention; and

Fig. 4 is a section on the line 4—4 of Fig. 3.

Referring to the accompanying drawings, the loom frame has mounted thereon, as 60 usual, the warp beam 1 from which the warp threads *a* pass over the usual whip roll 2, then to the warp stop mechanism, and from there through the shedding mechanism or harnesses 3, from which point the warp 65 threads extend through the usual reed 4 mounted on the lay 5. The finished cloth *b* extends over the take-up roll 6 and, as usual in looms of ordinary construction, the woven cloth is taken up as woven, but since 70 the details of these features form no part of the present invention, it is not deemed necessary to describe them in detail.

As shown in the present instance of the invention, the warp stop mechanism is located between the shedding mechanism or harnesses 3 and the rear of the loom or whip roll 2. Extending upwardly from the loom frame are the brackets 7, one at each side of the loom, and adjustably mounted upon the brackets are the side supporting frames 8 of the warp stop mechanism, which in the present instance are shown as provided with a foot portion 9 which may be secured to the supports 7 by bolts 10.

85 The side members 11 of the warp stop mechanism are shown in the present instance as providing a rest over which the warp threads *a* pass on their way from the warp beam to the front of the loom.

90 Each of the side brackets 8 provides supporting means for the drop wire detector mechanism which is associated with the drop wires to effect loom stoppage either when a warp thread breaks or becomes too slack, or 95 is unduly tensioned, as will more fully appear.

As more clearly illustrated in Figs. 2, 3 and 4, the drop wire detector 12 extends transversely of the loom between the supports 8 and is given a detecting movement in a direction transversely of the loom. In the present instance, the drop wire detector 12 has drop wire engaging teeth or notches, not only along its upper edge, as indicated, but similarly along its lower edge, so that should a drop wire be released by a warp thread becoming broken or too slack, it will arrest

the detector and effect loom stoppage. On the other hand, should a drop wire be unduly raised by an abnormally tensioned warp thread, it will engage the teeth along 5 the lower edge of the detector and similarly effect loom stoppage.

In the present instance of the invention, the side brackets are provided with transversely extending slots, as indicated in Fig. 10 2, and have secured therein one or more stationary toothed bars 13, two being shown in the present instance of the invention, but it being understood that only one of such stationary toothed bars may be used, as is 15 common in the art. The detector 12 is provided with a slot 14 by which may be permitted its movement transversely of the loom and relative to the usual securing bolt 15. Along the top edge portion of the detector 12 are a series of teeth 16 thereby providing between each adjacent tooth a space 17 at the upper edge of the detector which may be engaged by the top portion of a drop wire 18 having an elongated slot 19, as usual. 20 Likewise the stationary bars 13 are provided with similar teeth 20 along their upper edges, and the detector 12 is given a transverse movement relative to the toothed stationary bars, the construction being such that should a drop wire fail to be supported 25 by its warp thread, it will drop and engage between the teeth of the detector and stationary bars and thereby arrest movement of the detector which through a train of mechanism 30 thereby effects loom stoppage.

The detector 12 is similarly provided along its lower edge with a series of teeth 21 which may be of substantially the same character as the teeth along the upper edge, and 40 similarly, the stationary bars 13 are provided with a series of teeth 22 along their lower edges, so that should a drop wire be abnormally raised by a tensioned warp thread due to a cross in the warp, the lower portion of the slot 19 in each drop wire will engage between the lower teeth in the detector and stationary bars 13 and arrest the detector, to thereby effect loom stoppage.

The teeth along the upper and lower edges 50 of the detector are herein indicated as substantially rectangular in form but of course the shape of the teeth may be varied as may also the teeth on the stationary bars 13.

The drop wires 18 are each provided with 55 an opening 23 through which a warp thread passes, with the result that normally the drop wires will be held in a normal weaving position, so that the detector 12 may partake of its detecting movement in a direction transversely of the loom without engaging a drop wire either at the upper or lower end of the elongated slot 19, as indicated at the right in Fig. 2, but instead of forming the eyes or openings 23 in the drop 60 wires, they may be provided with any other

usual form of warp engaging element for sustaining the drop wires by the normally conditioned warp threads.

In the illustration in Fig. 1, the drop wires 18 are arranged in two banks, but it will be 70 obvious that any number of banks of drop wires may be employed.

In accordance with the present invention, the detector 12 is given a reciprocating movement transversely of the loom, and to 75 effect such movement any suitable train of mechanism may be employed, but as indicated in Fig. 1 the end support 8 of the warp stop mechanism has mounted thereon the rock shaft 24 carrying a rocking seat 25 for the actuator 26 which may tilt relative to the seat 25 about its end portions 27, and the rock shaft 24 is connected by an arm 28 to a rod 29 which has imparted thereto the usual movements of this type of warp stop mechanism to impart the transverse movement to the detector. The actuator 26 has associated with it an arm 30 pivotally mounted at 31 and connected at 32 to the actuator, the construction being such that should the detector be arrested in its transverse movements, the actuator 26 will be stopped, and consequently turned about one of its supports 27, as indicated in Fig. 1, to thereby actuate the arm 30 and through a sheathed wire 33 position a dog 34 in the path of a bunter 35 secured to the lay 5. The dog 34 has connected to it a pull rod 36 which extends frontwardly and is connected to the shipper mechanism to effect 100 loom stoppage whenever the transversely movable detector is arrested in its detecting movements.

The details of the detector actuating means and the stopping mechanism rendered operative by the arrest of the detector may all be of the same general character as more fully shown and described in the patent to Harry A. Davis and Arthur S. Johnson, No. 1,538,625, May 19, 1925, to which reference 110 may be had for a more full disclosure of the details thereof.

When, during the weaving operation, a warp thread becomes broken or too slack for weaving purposes, the associated drop wire will drop and engage the upper teeth in the detector, thereby effecting loom stoppage. On the other hand, should a cross occur in the warp threads, one or more of the warp threads will be unduly tensioned in the formation of the shed and thereby raise the associated drop wire from its normal to its abnormally raised position, as indicated at the left, Fig. 2, thereby causing the lower end portion of the slot 19 to bring the lower wall of the slot into engagement with a tooth along the lower edge of the detector and thereby arrest its detecting movement, which acts similarly as above described to effect loom stoppage. From the 120

construction described thereof it will be noted that the loom will be stopped should a warp thread break or become too slack for weaving purposes, and similarly the loom will be stopped should one or more of the warp threads become unduly tensioned, so that the weaver may remedy the warp fault without the production of imperfect cloth.

10 It has not been deemed necessary herein to describe in detail the actuating means for the transversely movable detector, nor to describe the details of the means for effecting loom stoppage when the detector movement is arrested either by an abnormally raised or by an abnormally lowered drop wire, because the details of such mechanism for moving the detector and effecting loom stoppage when its detecting movement is arrested are all fully shown and described in the patent hereinbefore mentioned.

What is claimed is:

1. In a warp stop mechanism for looms, the combination of a series of drop wires normally supported by the warp threads during weaving, a drop wire detector exerting a detecting movement transversely of the loom and provided with a series of teeth on both its upper and lower edges for engaging a drop wire when it is abnormally lowered by a broken or too slack warp thread or abnormally raised by an unduly tensioned warp thread, and loom stopping means for stopping the loom when the detector movement is arrested by an abnormally low or abnormally high drop wire.

2. In a warp stop mechanism for looms, the combination of a series of drop wires supported in normal position by the warp threads during weaving, a drop wire detector having a detecting movement in a direction transversely of the loom and provided with a series of teeth on its upper edge for engagement by a drop wire when in an abnormally low position and a series of teeth

on its lower edge for engagement by a drop wire in an abnormally raised position, and means for stopping the loom when the detector movement is arrested by either an abnormally lowered or an abnormally raised drop wire.

3. In a warp stop mechanism for looms, the combination of a shedding mechanism, a series of drop wires normally supported by the warp threads during weaving, a detector having a detecting movement transversely of the loom and provided with a series of teeth along its lower edge for engagement by a drop wire when it is abnormally raised by an unduly tensioned warp thread, and means for stopping the loom when the detector movement is arrested by an unduly raised drop wire.

4. In a warp stop mechanism for looms, the combination of a shedding mechanism, a series of drop wires having elongated slots and normally supported by the warp threads during weaving, a drop wire deflector having tending through the slots of the drop wires and provided with a series of teeth along its lower edge and having a detecting movement transversely of the loom, and means for stopping the loom when the detector movement is arrested by an abnormally raised drop wire engaging a tooth along the lower edge of the detector.

5. In a warp stop mechanism for looms, the combination of a series of drop wires normally supported by the warp threads during weaving, a transversely movable detector having teeth along its upper and lower edges, a stationary toothed bar extending transversely of the loom and having teeth along its upper and lower edges that the movable detector may be arrested in its detecting movement by an abnormally raised or an abnormally lowered drop wire.

In testimony whereof, I have signed my name to this specification.

ISAAC SNOW.
